UNITED STATES PATENT OFFICE.

VITUS A. BOKER, OF MINNEAPOLIS, MINNESOTA.

CHECK-PROTECTOR.

1,385,168.

Specification of Letters Patent. Patented July 19, 1921.

Application filed March 6, 1920. Serial No. 363,727.

To all whom it may concern:

Be it known that I, VITUS A. BOKER, a citizen of the United States, residing at Minneapolis, in the county of Hennepin and State of Minnesota, have invented certain new and useful Improvements in Check-Protectors; and I do hereby declare the following to be a full, clear, and exact description of the invention, such as will enable others skilled in the art to which it appertains to make and use the same.

My invention has for its object to provide an extremely simple, yet efficient check protector, capable of being made in small size that is adapted to be carried in a vest pocket; and to such ends generally stated, the invention consists of the novel devices and combinations of devices, hereinafter described and defined in the claims.

20 The device is preferably made in disk-like form and comprises three main elements to wit: A disk-like die plate, a disk-like stripper plate and a punch plate, the latter being formed with radial punch arms, and 25 the three plates being connected at their centers by a rivet or the like.

The punch arms are provided with heads having punch pins arranged to form characters, and these punch pins work freely 30 through the openings in the stripper plate but closely fit correspondingly arranged perforations that afford pin seats in the die plate. The stripper plate is spaced from the die plate far enough to permit a bank 35 check to be freely inserted edgewise between the same. The punch arms are of spring tempered steel and they normally stand 40 away from the stripper plate with sufficient clearance to permit the punch pins to be forced from their normal or retracted positions down through the check and into the 45 perforations or pin seats of the die plate.

The improved check protector is illustrated in the accompanying drawings, 45 wherein like characters indicate like parts throughout the several views.

Referring to the drawings:

Figure 1 is a plan view of the check protector, a portion of the bank check being indicated by dotted lines;

Fig. 2 is an enlarged fragmentary view of a portion of the protector, said parts being shown in plan view;

Fig. 3 is a plan view of the die plate, other parts of the protector being removed therefrom; and

Fig. 4 is a section on the line 4—4 of Fig. 2.

The disk-like die plate is indicated by the numeral 5 and the punch seats, which are 60 perforations in the seat plate, are indicated by the numeral 6. These perforations 6 are arranged to represent the different characters and are shown that there are 10 of these characters, including the digits 0 to 9 65 inclusive and in addition an 11th character, the latter being of two rows of parallel lines of perforations and which latter character, it may be here noted, will be used before the first punched numeral and after 70 the last punched numeral applied to the check.

The stripper plate is indicated by the numeral 7 and the so-called punch plate is indicated by the numeral 8, the latter being 75 of smaller diameter but having a plurality 80 to wit, eleven radially projecting spring arms 9, that terminate in heads 10. The heads 10 are preferably thicker than the arms 9 and they are marked with the numeral or characters corresponding to the digits and the additional character on the die plate. The three plates 5, 7 and 8 are rigidly connected at their centers by a rivet 10^a, and spacing washers 11 and 12 are 85 interposed respectively between the plates 5—7 and 7—8, the washer 12 constituting a gage for the edge of the check. (See particularly Fig. 4.)

The heads 10 of the several spring arms 9 90 are provided with punch pins 13, which as is already stated, work freely through the stripper plate 7 and are arranged to correspond to the perforations 6 of the die plate, so that one punch pin will enter each of 95 said perforations when a head 10 is pressed toward the die plate. The spring tension of the arms 9 is such that the punch pins 13 are normally retracted from the perforation 6 and will be drawn into but not 100 through the stripper plate 7. (See Fig. 4.) The so-called punch plate 8 and its arms 9 are preferably stamped from a single piece 105 of sheet steel that is capable of being spring tempered and the rivet 10 will be so tightly applied that the punch pins 13 cannot get out of alignment with the coöperating pin sheets of the perforating die plate 5.

In Fig. 1 a portion of a bank check is indicated by the character y. The manner 110 of using a check protector of this general character, is of course, well understood.

The check may, of course, be inserted freely between the stripper plate 7 and the die plate 5 with the particular character or numeral that is to be punched in proper position by action on the check and then by placing the proper head 10 toward the die plate, the punching action is produced. Thus, by the use of this simple device, the proper numeral indicating a certain limit 10 of the value of the check, may be quickly stamped on the check, the numeral on the check represented by perforated characters.

It is highly important to note that the stripper plate 7 is formed with a notched periphery, so that it is provided with an opening or crotches 7^a located between the punch heads 10 and extended radially inward thereof, so that the operator can readily see on what part of the check the characters are being punched, and thus good alinement, and proper spacing of the several characters on the check is made possible.

In practice, this check protector has been made of such small size, that it will be contained and concealed entirely in a vest pocket, but is nevertheless found to be highly efficient for the purposes had in view.

80 What I claim is:

1. A check protector adapted to be carried

in a check book having in combination, a die plate having perforations forming the characters to be punched, said perforations being constructed as female die members 35 opening through the bottom of the protector and being unobstructed to permit discharge of the punchings, a stripper plate circumferentially notched and formed with radial projecting portions having perforated characters alining with the perforations in said die plate, and a punch plate having radial arms carrying punches arranged to form the characters to be punched, the ends of said punches being flat and perpendicular to the 40 sides thereof and adapted to coöperate with the dies in the die plate to completely sever the portions of the check, said stripper plate being disposed between the die and punch plates.

2. The combination set forth in claim 1, and a circular washer interposed between the punch plate and stripper plate and constituting a gage member with which the edge of the check is adapted to contact.

In testimony whereof I affix my signature in presence of two witnesses.

VITUS A. BOKER.
